UNITED STATES PATENT OFFICE

2,286,003

MOVABLE LINTEL FOR VERTICAL DOORS

Clifford Norton, Summit, and Benjamin Whitehead Tucker, Jr., South Orange, N. J., assignors to Otis Elevator Company, New York, N. Y., a corporation of New Jersey.

Original application July 17, 1941, Serial No. 402,796. Divided and this application February 19, 1942, Serial No. 431,546

5 Claims. (Cl. 187—51)

The invention relates to mechanism for vertical bi-parting pass type elevator hatchway doors for closing the space between the top of the upper door section and the soffit of the hatchway opening.

This application is a division of application Serial Number 402,796 of Clifford Norton and Benjamin Whitehead Tucker, Jr., filed July 17, 1941.

In freight elevator installations such as in factories and warehouses, many of the elevators are of large capacity and it is desirable in installations such as these that wide openings be provided at the floors to afford access to and from the cars. Vertically movable bi-parting doors are especially suitable for such installations inasmuch as with such doors, the door openings can be made as wide as the car. The door sections are guided on vertical guides and are connected together in counterbalancing relationship so that even though the doors are large and heavy, they are easy to operate. It is desirable that such doors be of sturdy construction that they may readily be repaired as they are subject to hard usage. Also fire protection is an important factor in buildings of such character and it is desirable that the doors provide an effective seal of the hatchway openings against smoke and flame. Flame angles are provided to form a seal along the sides of the door sections while the joint between the abutting door sections when closed is sealed by an astragal secured to the bottom of the upper door section. The door sections overlap the top and bottom of the hatchway openings and in case the doors are of the pass type, the space between the top of the upper door section and the soffit of the hatchway opening is sealed by a lintel which is movable to enable the lower section of the door above to move to open position overlapping this upper section. It is desirable that the door be constructed so as to effectively retain these seals under the influence of heat and water. In insuring such buildings, special consideration is given hatchway doors of a construction which have passed certain fire tests provided by the underwriters' laboratories.

The object of the invention is to provide a movable lintel, for closing the space between the top of the upper section of a vertical bi-parting pass type door, and the hatchway wall which is of simple but sturdy construction and reliable in operation and which provides an effective seal in case of fire.

In carrying out the invention according to the 55 top of the sill when the door is closed. Each

arrangement which will be described, a movable lintel is carried by the lower door section of the door above so as to move therewith, being guided on the same guide rails as this lower section.

5 The lintel is in the form of an elongated channel member and takes up the space between the top of the upper section of the door and the soffit of the door opening. The lintel is hung on rods depending from the lower section of the door above which slide into this section should the lintel upon the opening of the door above strike the astragal, as in the cases of short floor heights. This construction provides an effective seal against flame and smoke and is not disturbed by fire pressure within the hatchway.

A general idea of the invention, the mode of carrying it out which is at present preferred, and the various features and advantages thereof will be gained from the above statements. Other 20 features and advantages of the invention will be apparent from the following description and appended claims.

In the drawings:

Figure 1 is a schematic representation in rear elevation, with certain parts omitted, of a vertical bi-parting counterbalanced pass type hatchway door embodying the invention, illustrating the application of both power operating mechanism and locking mechanism to the door;

25 Figure 2 is a fragmental view similar to Figure 1, in which the door is hand operated;

Figure 3 is an enlarged view in rear elevation of a portion of the vertical bi-parting counterbalanced pass type hatchway door of Figure 1, 35 illustrating details of construction;

Figure 4 is a side view of the same;

Figure 5 is an enlarged view in section taken along the line 5—5 of Figure 3;

Figure 6 is an enlarged view in section taken 40 along the line 6—6 of Figure 3;

Figure 7 is an enlarged view in section taken along the line 7—7 of Figure 3; and

Figure 8 is a top view of one edge of the movable lintel taken from above the lintel.

45 Referring to Figure 1, the door 15 is illustrated as a vertical bi-parting door positioned for closing an elevator hatchway opening indicated by floor level 16 and soffit 17. The upper section of the door is designated 20, while the lower section is designated 21. The upper section is provided with a vision panel 19. The top of the lower section is provided with a truckable sill 22. The bottom of the upper section is provided with rubber bumpers 23 which rest on the

section is provided with a plurality of guide shoes 24, two on each side thereof. The guide shoes for the lower section cooperate with guide rails 25, while those for the upper section cooperate with guide rails 26. The sections are connected together in counterbalancing relationship. This is effected on each side of the door by a chain 27 connected to a bracket 28 secured to the side of the upper door section at the bottom. From the bracket the chain extends upwardly and over a sheave 30 and is connected through a rod 31 to the end of sill 22. The supporting bracket 32 for sheave 30 is secured to the guide rail 26.

An elongated bar 33 is secured on the right hand side of the upper door section to angles 34 in turn secured to the door section. This bar serves as a lock bar, being engaged by the notched end of a latch lever 35 when the door is closed to lock the door sections against opening movement. This lever is secured to a pivot shaft 36 rotatably supported on bracket 32. Secured to shaft 36 is a lever 37 which carries an operating roller 38. This roller is adapted to be engaged by a retiring cam carried by the elevator car to move the latch lever into position to disengage the lock bar and unlock the door. This cam is retracted during operation of the car so as to clear the operating rollers for the door locks for the floors at which stops are not to be made.

The latch lever may also be operated manually through a bell crank lever 40 pivotally mounted on the inside of the upper door section near the bottom and central of the door. One arm of this lever serves as an operating handle and the other arm is connected by a rod 41 to a second bell crank lever 42 which is connected to a vertical rod 43. The lever 42 is weighted to counterbalance the weight of the rod. The rod 43 is bent inwardly near its upper end and then back to form a cam 44. The upper end of this rod extends through a guide aperture in a bracket 45 secured to the top of the door section. This cam when pulled downwardly engages a pin on latch lever 35 to unlock the door. This downward movement is effected by clockwise movement of operating lever 40, a stop 46 being provided to limit the movement of this lever. Continued pushing on operating lever 40 after it engages stop 46 moves the door to open position. The latch lever 35 is arranged to operate switching mechanism 48 when the door is unlocked, this being effected through a link 50 connecting the switching mechanism to a lever 51 on shaft 36.

Contacts of switching mechanism 48 control the operation of motor 53 which provides the power for moving the door sections to open and close positions. This motor is mounted on a bracket 54 secured to the guide rail 26 at one side of the door, this bracket being also secured to the hatchway wall in certain instances to provide extra support. This motor drives a sprocket 55 through gear reduction 52, the sprocket in turn driving a sprocket chain 56. One end of this chain is secured to the sill 22 from which it extends upwardly over sprocket 55, thence downwardly and around another sprocket 57 and thence back to sill 22 to which the other end of the chain is secured. A shaft 58 extends across the lower door section beneath the sill being supported in bearings 60 depending from the sill. At each end of this shaft is secured a sprocket 61 which meshes with a stationary chain 62. These chains are secured to guide rails 26 through brackets 63 and 64, the connections being through eye bolts 65 in order that the chains may be adjusted and

kept taut. These chains serve as racks upon which the sprockets move during operation of the door and prevent tilting of the door about an axis perpendicular to the plane of the door.

5 Shoes 59 are provided for maintaining the sprockets in mesh with the chains. Stops 66 are secured to guide rails 26 in position to engage the ends of sill 22 when the door is open to support the lower section with the sill in line with the 10 floor level 16. The sprocket 57 acts through gearing 67 to operate further control switching mechanism 68 for the motor, this switching mechanism being mounted on bracket 64.

In operation, as the car stops at the floor, the 15 retiring cam is extended and engages roller 38 swinging lever 35 into position to disengage the lock bar 33, unlocking the door. Also, certain contacts of switching mechanism 48 are engaged causing the energization of motor 53 for rotative movement of sprocket 55 counterclockwise. This sprocket acts through chain 56 to pull down on the lower door section. At the same time the upper door is pulled upwardly through its connection to the lower door section by chain 27. 20 Thus the two sections counterbalance each other minimizing the load on the motor. The door is brought to a stop upon the engagement of the truckable sill with stops 66. During the door opening operation motor 53 is controlled by 25 switching mechanism 68 to be slowed down as the door nears open position. To close the door, the motor is energized for reverse rotative movement and acts through chain 56 to pull up on the lower door section. At the same time the upper section, being released by upward movement of the lower section, closes by its own weight. The sections are brought to a stop upon the engagement of the bumpers 23 with the truckable sill. During the closing movement, motor 53 is controlled by 30 switching mechanism 68 to be slowed down as the door nears closed position. The operating mechanism above described is the subject matter of the copending application of Norton, Karmel and Tucker, Serial Number 368,424, filed December 4, 35 1940.

Referring to Figure 2 the construction is the same as Figure 1 except that no power operation is provided and the control of the lock is modified. A bar 70 is slidably supported in a bracket 71 secured to the upper door section and is connected to bell crank lever 40. The end of a lever 72 extends in the path of movement of the left hand end of this rod. This lever is mounted on a shaft 73 rotatably supported by a bracket 74 secured to the guide rail 26. Also secured to this shaft is a lever 75, the upper end of which carries an operating roller 76. This roller is adapted to be engaged by a stationary cam carried by the elevator car to move lever 72 into position out of the path of movement of bar 70 when the car is stopped at the floor. This enables clockwise movement of operating lever 40 to unlock and open the door by hand. However, when the car is away from the floor, the cam is disengaged from the roller so that lever 72 is in the path of movement of rod 70 preventing the unlocking of the door.

Referring now to Figures 3 and 4, the upper section 20 and the lower section 21 of the door each comprises a frame 80 made up from an angle 84 bent at right angles at the corners, the ends being joined together as by welding. The space inside the frame is filled in with panels 82 and 83 abutting vertical stiffener bars 81.

Flame angles 92 are secured as by welding to the sides of the frame.

The truckable sill 22 is secured as by plug welding to the top angle of the frame of the lower door section. This sill is in the form of an angle member, the vertical leg of which extends downwardly parallel to the plane of the door. This sill is wider than the door section extending substantially the width of the hatchway. The purpose of this arrangement will be seen from further description. A toe guard 95 is secured to the vertical leg of the truckable sill by screws 96 arranged at spaced intervals. This toe guard extends well into the troughs formed by the panels being provided with slots 97 to clear the joints between the panels and the vertical bars 81. Another toe guard 100 is provided at the bottom of the lower section. This toe guard, as shown in Figure 7, is secured by screws 101 to angle brackets 102. These angle brackets are positioned at spaced intervals and are welded to a stiffener bar 103 in turn secured by bolts 104 to the bottom of the frame. The apertures 105 in the frame through which the bolts extend are elongated to allow for relative expansion between the bar and the frame in case of fire. The stiffener bar and the truckable sill minimize warping of the lower door section in case of fire upon the sudden cooling of the door.

An astragal 110 extends across the bottom of the upper door section and is secured to the frame by bolts 111 at spaced intervals. As in the case of bolts 104, the bolts 111 extend through elongated slots 112 in the frame to allow for relative expansion between the astragal and the frame in case of fire. The astragal is in the form of an angle member the vertical leg of which extends downwardly to cover the space 113 between the door sections when the door is closed, thereby providing a seal against smoke and flame. A plurality of steel bars 115 are provided on top of the upper door section, being secured to the frame by bolts 116 at spaced intervals. Elongated slots 117 are provided in the bars through which the bolts extend to allow for relative expansion between the bars and the frame. These bars serve as stiffener bars and act to minimize bulging of the door section at the soffit in case of fire. They also add weight to the door section for counterbalancing the upper door section with the lower. Inasmuch as it is undesirable to have too many of these bars, the astragal is formed of heavy stock to assist in providing the counterbalance.

In the case of pass type doors a space 180 exists between the top of the upper door section and the hatchway wall at the soffit 17. To seal this space against flame and smoke a movable lintel is provided. This lintel is in the form of a channel member 181 extending in space 180 across the door opening. This lintel is supported by a plurality of rods 182 extending at spaced intervals downwardly from the lower section of the door above. These rods extend through apertures 183 provided in the channel member and the lower ends are threaded to receive nuts 184 upon which the channel member is supported. These rods extend upwardly through apertures 189 in toe guard 100. The upper ends of these rods extend through apertures 185 and 186 in the stiffener bar 103 and the door frame respectively of the lower section of the door above. The apertures 186 are elongated to permit relative expansion between the bar and the frame. The upper ends of the rods are threaded to receive

adjusting and lock nuts 187 which support the rods to position the channel members in line with the top of the door opening. A plate 188 may be secured to the channel at each end thereof to form a flame seal, each plate being provided with a slot to span the guide rail. On top of the plate is secured a guide shoe 190, the plate and guide shoe being secured to the channel by bolts 191. The guide shoes 190 slide on the same guide rails 25 as the lower door sections, each shoe being provided with a slot 192 into which the guide leg of the guide rail extends.

With this construction the movable lintel is raised and lowered with the door section to which it is secured and when the door is closed forms a dependable and effective seal for the opening 180. The construction is very sturdy and is not disturbed by fire pressure within the hatchway. In certain installations due to the relationship of floor heights and door sizes it may be that in opening the door the lintel will strike on the astragal of the door below before full opening is reached. In such cases the rods 182 are pushed upwardly into the lower door section until this section reaches full open position. When the door is closed the door frame moves up into position engaging the nuts 187 thereby picking up the rods and thus the lintel to move it back into sealing position as the door is closed.

As many changes could be made in the above construction and many apparently widely different embodiments of this invention could be made without departing from the scope thereof and as the invention is applicable to doors of other constructions, it is intended that all matter contained in the above description or shown in the accompanying drawings shall be interpreted as illustrative and not in a limiting sense.

What is claimed is:

40. 1. In an elevator system in which a vertical bi-parting counterbalanced hatchway door is provided at each of a pair of adjacent floors and in which the lower section of the door for the higher floor in opening overlaps the upper section of the door for the lower floor, an elongated member closing the space between the upper part of said upper section and the hatchway wall at the soffit of the opening for the door for the lower floor when the doors are closed, and means for supporting said member from the bottom of said lower section, said supporting means being yieldable to permit full opening of said lower section in the event said member is brought to a stop by said door for the lower floor before said lower section reaches full open position.
45. 2. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
50. 3. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
55. 4. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
60. 5. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
65. 6. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
70. 7. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.
75. 8. In an elevator system in which a vertical bi-parting counterbalanced hatchway door is provided at each of a pair of adjacent floors and in which the lower section of the door for the higher floor and the upper section of the door for the lower floor have guide rails arranged so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and means for supporting said channel member from the bottom of said lower section, said supporting means yielding to permit full opening of said lower section in the event said channel member is brought to a stop by said door for the lower floor before said lower section reaches full open position.

3. In an elevator system in which a vertical bi-parting counterbalanced hatchway door is provided at each of a pair of adjacent floors and in which the lower section of the door for the higher floor and the upper section of the door for the lower floor have separate guide rails spaced so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, and a plurality of vertical rods arranged at spaced intervals supporting said channel member, said rods being supported from the bottom of said lower section and extending upwardly into said lower section through apertures provided in the bottom thereof, said rods sliding up into said lower section to permit full opening thereof in the event said channel member is brought to a stop by said door for the lower floor before said lower section reaches full open position.

4. In an elevator system in which a vertical bi-parting counterbalanced hatchway door is provided at each of a pair of adjacent floors and in which the lower section of the door for the higher floor and the upper section of the door for the lower floor have separate guide rails spaced so that said lower section in opening may overlap said upper section, a movable lintel for closing the space between the upper part of said upper section and the hatchway wall at the soffit of the opening for the door for the lower floor when the doors are closed, said movable lintel comprising an elongated channel member, a plurality of vertical rods arranged at spaced intervals supporting said channel member, said rods being supported from the bottom of said lower section and extending upwardly into said lower section through apertures provided in the bottom thereof, said rods sliding up into said lower section to permit full opening thereof in the event said channel member is brought to a stop by said door for the lower floor before said lower section reaches full open position, the bottom of said lower section in the closing of said lower section

cooperating with said rods to pick up said channel member to restore it to said space closing position, and guide shoes secured to the ends of said channel member for cooperating with said guide rails for said lower section to guide said channel member in its movement during opening and closing of said lower section.

5. In an elevator system in which a vertical bi-parting counterbalanced hatchway door is provided at each of a pair of adjacent floors and in which the lower section of the door for the higher floor and the upper section of the door for the lower floor have separate guide rails spaced so that said lower section in opening may overlap said upper section, said upper section having an astragal secured to the bottom thereof, a movable lintel for closing the space between the upper part of said upper section and the hatchway wall at the soffit of the opening for the door for the lower floor when the doors are closed, said movable lintel comprising an elongated channel member, a plurality of vertical rods arranged at spaced intervals supporting said channel member, said rods being supported from the bottom of said lower section and extending upwardly into said lower section through apertures provided in the bottom of said lower section, the upper ends of the rods being threaded, nuts on the threaded ends of said rods for adjusting the effective length of the rods and for cooperating with said bottom of said lower section for supporting the rods, said rods sliding up into said lower section to permit full opening thereof in the event said channel member is brought to a stop by engaging said astragal before said lower section reaches full open position, the bottom of said lower section in the closing of said lower section engaging said nuts to pick up said channel member to restore it to said space closing position, and guide shoes secured to the ends of said channel member for cooperating with said guide rails for said lower section to guide said channel member in its movement during opening and closing of said lower section.

CLIFFORD NORTON.

BENJAMIN WHITEHEAD TUCKER, JR.
